[57] **CLAIM**

The ornamental design for a countertop air oven, as shown and described.

DESCRIPTION

FIG. 1 is a front left perspective view of a countertop air oven showing our new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

The food shown in broken lines in FIG. 1 is shown for illustrative purposes only and forms no part of the claimed design.

FIG. I

FIG. 2**FIG. 3**FIG. 5

FIG. 6

FIG. 7
